FLUID FEEDING DEVICE

Charles J. Eacock, Kansas City, Mo., and Claude H. Clauser, deceased, late of Kansas City, Mo., by Celeste H. Clauser, administratrix, South Pasadena, Calif.

Application June 22, 1933, Serial No. 677,092

17 Claims. (Cl. 184—27)

This invention relates to improvements in fluid feeding devices, and more particularly to means for feeding fluid, such as a lubricating medium, under pressure automatically in substantially direct proportion to the movement of the operating parts of a member with which the device is associated, and this application is a continuation-in-part of the application of Charles J. Eacock and Claude H. Clauser for patent on Metering fluid feeding devices Serial No. 310,899, filed October 6, 1928, now Patent No. 1,940,793, patented December 26, 1933.

It is a purpose of this invention to provide fluid feeding means that is adapted for use in feeding any fluid in measured quantities controlled by the movement of certain cooperating parts, but is particularly adapted for use as a lubricating device, and which is so constructed as to economize on the amount of lubricating fluid dispensed to each of the parts to be lubricated by supplying the proper amount of lubricant to the parts, but not a needless excess.

It is a further purpose of this invention to provide a device of the above mentioned character which is simple in construction and can be made at relatively small cost. While several specific forms of this invention are shown and described herein, the principle of operation of all thereof is the same, the differences between the various forms being largely in the cost of production thereof, certain forms being simpler and less expensive, while not as mathematically accurate, whereas other forms are somewhat more complex, but capable of the most exact metering in exact proportion of the movement of the operating parts. It will be obvious that it will be unnecessary to use such absolutely accurate metering where the movement of the parts is relatively large, whereas, where the movement of the parts relative to each other is minute, the metering means will have to respond immediately and operate substantially absolutely exactly in proportion to the movement of the parts to which lubricant is fed by the device.

While reference is made above to a simpler and more complex construction of the device, all forms of the invention are of a comparatively simple construction, which is strong and durable and all forms of the invention are automatic in operation, feeding or supplying lubricant or other fluid proportionately to the movement of the parts of the mechanism with which the same is associated.

It is a further purpose of this invention to provide new and improved means for producing the feeding movements of the feeding member pro-

portionately to the movement of the parts to which lubricant is fed, which comprises one-way clutch mechanism. The feeding member preferably has a reciprocatory movement, and the means for producing this movement is so constructed as to produce a measured movement of the feeding member in proportion to the movement of the parts with which the device is associated, and said means is positively driven in one direction by even a small movement of the parts to produce a corresponding movement of the actuating mechanism. The clutch mechanism is simple in construction and is so made that the parts thereof can be simply and cheaply made.

The novel actuating mechanism for the feeding member comprises a member that is rotatable only in one direction, which, in one form of the invention is shown as being a rotatable member cooperating with a stationary cam, and in another form of the invention as being a rotatable cam cooperating with a stationary member on which said cam acts. The means for rotating said rotatable member in only one direction comprises an oscillating clutch member, which moves the rotatable member in one direction of its movement, but moves individually of said rotatable member when rotating in the opposite direction, and a holding member that prevents the reverse rotation of the rotatable member with the oscillating clutch member. Preferably the holding member is also a one-way clutch device operating in a reverse direction to the driving clutch. The holding clutch member is stationary, while the oscillating clutch member moves with the movable part of the device with which the feeding device is associated.

The one-way clutch members are similar in construction, but operate reversely, and while an expanding coil spring clutch device is preferable in the simplest and cheapest form of the invention, a double ball clutch device is preferable where great accuracy is required. In the case of the expansible resilient clutch device the same comprises a resilient coiled member made up of two coiled parts and a connecting portion, the coiled parts being oppositely wound and the one coil member acting as a gripping or clutch member for driving movement, and the other oppositely wound coil member acting as a gripping or clutch member for holding the parts against movement in the reverse direction. The ball clutch members used in the more extremely accurate form of the invention are similar in construction and each comprises a disk-like member having cam or wedging faces thereon,

and a disk-like annular member embracing said member having the cam or wedging faces thereon and balls confined between said annular and cam faced members to wedge therebetween to 5 cause the parts to move together or to be held from movement as desired.

The fluid feeding means is designed to feed the fluid at a very high pressure, the action being obtained by means of a spring cooperating with 10 the cam member to produce a snap action of the feeding member in a feeding direction, the feeding member being of relatively small cross section, whereby a relatively strong spring of relatively large size is adapted to apply a relatively 15 high pressure per square inch effective on the face of the feeding member operating on the fluid.

The rotatable means, whether a cam or a member cooperating with a cam which rotates in only 20 one direction, acts to produce a return movement of the reciprocatory feeding member against the action of the spring, and the cam is so shaped that the part cooperating therewith drops off the abrupt shoulder on the cam to produce the feeding movement by snap action due to the sudden 25 expansion of the spring, which has been gradually compressed during the rotation of the controlling means for the feeding member, which has been actuated by the one-way clutch device, 30 and the movement of the feeding member in a return direction will be in proportion to the movement of the parts to which lubricant is fed due to the provision of the one-way driving clutch means interposed between one of the relatively 35 movable parts to which lubricant is fed, and the rotatable member that serves to control the frequency of the feeding strokes of the feeding plunger.

It is a further purpose of this invention to 40 provide a device of the above mentioned character which is made of a small number of relatively small parts, which are so constructed that the same will operate reliably and yet the entire device will be very compact and small for ordinary purposes requiring little if any more space than fittings of lubricating devices now in use, which are not automatic in operation. The fluid 45 feeding devices are adapted for use either individually or in a series fed from a central reservoir, the pumping or feeding mechanism being the same for the devices, no matter how the fluid is supplied to the chamber in each thereof from which it is fed at high pressure into the bearing or other part that is to be lubricated.

55 Other objects and advantages of this invention will appear as the description of the drawings proceeds. We desire to have it understood, however, that we do not intend to limit ourselves to the particular details of structure shown or described, except as defined in the claims.

In the drawings:

Fig. 1 is a view partly in section and partly in elevation, showing the improved fluid feeding means applied to a spring shackle to feed lubricant thereto.

Fig. 2 is a fragmentary view in side elevation of the devices shown in Fig. 1.

Fig. 3 is a longitudinal sectional view through one of the feeding devices, fragmentary portions 70 of a pipe line being shown associated therewith and the ball valve, plunger, cross bar, and springs associated with the ball valve and plunger being shown in elevation.

Fig. 4 is a section taken on the line 4—4 of 75 Fig. 3, the plunger, ball and springs being shown

in elevation and the parts being shown in a different position than that shown in Fig. 3.

Fig. 5 is a section taken on the line 5—5 of Fig. 3.

Fig. 6 is a section taken on the line 6—6 of 5 Fig. 3.

Fig. 9 is a side elevation thereof.

Fig. 10 is a view partly in elevation and partly in section of the plunger and cross bar associated therewith.

Fig. 11 is a view partly in elevation and partly 15 in section taken on the line 11—11 of Fig. 10.

Fig. 12 is a view similar to Fig. 3 of a slightly modified device showing a double ball-clutch mechanism incorporated in the device.

Fig. 13 is a section taken on the line 13—13 of 20 Fig. 12.

Fig. 14 is a section taken on the line 14—14 of Fig. 12.

Fig. 15 is a section taken on the line 15—15 of 25 Fig. 12.

Fig. 16 is a view similar to Fig. 3 of a further modification, utilizing a single ball-clutch.

Fig. 17 is a view similar to Fig. 3 of a modification of the device in which the double ball-clutch is utilized, and the cam rotates instead 30 of being stationary.

Fig. 18 is a section taken on the line 18—18 of Fig. 17.

Fig. 19 is a section taken on the line 19—19 of 35 Fig. 17, and

Fig. 20 is a section taken on the line 20—20 of Fig. 16.

Referring in detail to the drawings, in Fig. 1 is shown a feeding member having a housing 21 and a base portion 22, the base portion being 40 connected with a screw threaded opening in a flange 23 provided on a shaft 24 on which a crank member 25 is mounted to rotate therewith, said shaft oscillating in a bearing 26 mounted on a frame member 27 and a lubricant 45 passage 28 leading to the bearing 26. A pipe line having the conduit portions 29 and 30 leading respectively into the housing 21 and the base member 22 is shown in Fig. 1, the conduit portion 29 being preferably fixed to the frame by 50 any suitable securing means 31. The feeding member having the housing portion 21 and the base portion 22 is shown more in detail in Figs. 3 to 9 inclusive.

The base portion 22 is provided with an externally screw threaded nipple portion 32, which is adapted to be threaded into a suitable threaded opening in a bearing, shaft, or any other device that is provided with a lubricant passage to which lubricant is to be fed. Said base portion is provided with a valve chamber 33 within which a coil spring 34 is mounted, which presses the ball valve 35 against a suitable annular seat 36 provided at the junction of the valve chamber 33 and the plunger receiving passage 37. The spring 65 is held in position in engagement with the ball valve 35 in compressed position by crimping over the material of the externally screw threaded nipple 32, as indicated at 38.

The base portion 22 is provided with a passage 70 39 intersecting the passage 37 and has a passage 40 leading to the passage 39 from a chamber formed between the housing portion 21 and the base portion 22. While obviously any suitable means could be provided for feeding lubricant 75

into this chamber and thus to the passage 39, and a supply of lubricant could be maintained in said chamber whether or not a pipe line were provided leading to said chamber, by manually filling the chamber at stated intervals, the form of the invention illustrated shows the feeding member interposed in a pipe line supplying lubricant from any suitable reservoir, the pipe or conduit 38 being screw threadedly received in an internally threaded opening 41 in the base member 22 which communicates with the passage 39, and the externally screw threaded portion of the pipe or conduit 38 being received in an internally screw threaded nipple 42 provided on the housing portion 21.

It will be noted that the passage 40 is sector shaped, this shape being used in order to obtain a relatively large cross sectional capacity for the passage without reducing the thickness of the wall of the base member to too great an extent. The parts are shown very much enlarged in Figs. 3 to 9 inclusive, being approximately three times the actual size, and inasmuch as the devices are so small it is desirable to utilize such a passage to maintain the outer wall portion thereof of such a size as to be ample for the necessary strength of the parts. Substantially concentrically arranged with the arcuate passage 40 is a plunger guide passage 43, in which a plunger rod 44 is slidably fitted for reciprocating motion, said plunger rod being adapted to be projected into the passage 37 from the position shown in Fig. 4 to that shown in Fig. 3.

The base member is provided with an annular groove 45 therein receiving a compressible gasket member 46, which is also seated in an annular groove 47 in the housing or cap member 21, the gasket member being preferably split as shown at 48 in Fig. 6, to simplify the assembly of the same in the groove 45. The gasket member 46 is rotatable in the groove 45, but is clamped in position in the groove 47, the annular inturned flange portion 49 on the housing or cap member being crimped around the gasket to hold it firmly in place and to provide a tight joint between said housing member and the gasket. Inasmuch as the liquid that might escape between the substantially cylindrical side wall portion of the base member 22 and the substantially cylindrical embracing wall portion of the housing 21 is under substantially no pressure, it will be obvious that a substantially fluid-tight joint is provided by the gasket member 46.

The base member 2 is further provided with a cam formed thereon in the recess provided in the end thereof that is received within the housing, said cam comprising a pair of diametrically opposite inclined cam portions 50, which rise gradually from a low point to a high point defined by an abrupt shoulder 51, there being a pair of such shoulders on the cam diametrically opposite each other and the cam being inclined upwardly in a clockwise direction.

Cooperating with the cam member is a follower in the form of a cross bar 52, which is mounted on the plunger rod 44 and which is substantially channel-shaped in cross section, and has a box-like portion, as shown in Fig. 11, and which has an opening 53 therein, through which the plunger rod 44 extends, said plunger rod having a head 54 formed thereon, which is mounted inside the substantially square passage in the box-like portion of the member 52, and which is formed by flattening the plunger rod 44 on opposite sides thereof so as to provide a flat narrow head por-

tion thereon. The closing wall 55 of the bar 52 extends only a short distance beyond the head 54 so as to prevent any endwise movement of the plunger 44 relative to said bar 52 and to provide a bearing member for the coil compression spring 56 of relatively large capacity, which is mounted between the closed end wall 57 of the housing and said follower 52, a shallow socket 58 being provided in the head 57 for seating the end coil of the spring 56. The side walls of the cross bar 52 are provided with a tapering extension 59, one of which serves as a driving finger for rotating the follower 52 and moving it along the inclined surface of the cam members 50.

Means is provided for driving the follower 52 by means of the housing member 21 so that the follower 52 will rotate with the housing member 21 in one direction, but will not rotate therewith in the opposite direction, but will remain stationary with the base member 22 while the housing member 21 is rotating in such opposite direction. This means comprises a one-way clutch mechanism for driving, and a one-way clutch mechanism for holding the member 52 from reverse rotation, but said one-way clutch members are incorporated in a single unit, which comprises an expandable coiled, resilient portion 60 and an expandable, coiled, resilient portion 61 connected by means of a substantially U-shaped open looped portion 62, the U-shaped portion 62 being in engagement with the extension 59 on the follower 52. The turns of the coiled portion 60 are seated in a chamber in the housing member 21, which has a cylindrical concave wall portion 63, with which the coils of the member 60 are in slight frictional engagement when the spring formed by the coils 60 is in normal condition. The spring portion 60 is so wound that when the housing member 21 is rotated in a clock-wise direction relative to the base member 22, the engagement of the end coil 40 of the spring frictionally with the shoulder 64 provided between the socket portion 58 and the chamber having the wall portion 63, and particularly the frictional engagement of the various coils with the curved wall 63 will cause the coils of 45 the expanding resilient clutch portion 60 to enlarge or increase in diameter, causing said clutch member to firmly grip the wall portion 63 and to rotate in unison with the housing portion 21, thus carrying the entire coiled portion 60 around in 50 a clockwise direction with the housing portion 21 and the U-shaped connecting portion 62 therewith, which, being in engagement with the extension 59 on the follower 52 will carry the follower 52 along with it in a clock-wise direction along 55 the inclined cam faces 50. This will continue as long as clockwise rotation of the member 21 relative to the member 22 takes place.

Due to the fact that the coiled portion 61 of the clutch unit is coiled in the opposite direction, it 60 will be reduced in diameter due to the rotation of the housing 21 relative to the base portion 22 in a clockwise direction and will rotate freely in the concave cylindrical wall portion 65 provided in the chamber for receiving said coiled 65 portion 61 in the end of the base member 22 confined in the housing 21, endwise beyond the cam with which the follower 52 engages, there being a shoulder 66 provided between the cam portion formed on the member 22 and the spring 70 clutch receiving chamber therein, with which the end coil of the expanding resilient clutch portion 61 engages.

Upon reverse rotation in a counter-clockwise direction of the housing member 21 relative to 75

the base member 22, there might be a tendency of the resilient clutch member 60 to rotate therewith in said counter-clockwise direction. Such rotation and consequent reverse rotation of the follower 52, is, however, prevented by the one-way holding clutch provided by the expanding coiled resilient clutch member 61, which, upon any tendency of the unit to rotate in a counter-clockwise direction will expand against the wall 65, firmly gripping the same and preventing any rotation of the unit in a counter-clockwise direction with the housing portion 21. As soon as such gripping of the coiled resilient clutch member 61 takes place the coils of the clutch portion 60 will be reduced in diameter and the clutch member entirely freed of the wall portion 63 to permit the housing to rotate around on the same in a counter-clockwise direction without having any effect on the mechanism controlled by the clutch, 20 the parts being ready to resume the driving of the follower 52 upon clockwise rotation of the housing 21 relative to the base member 22.

It will be understood that thus the oscillations of the member 21 relative to the member 22 and 25 the oscillations of the shaft 24 in the bearing 26, for example, or any other two relatively movable parts, will cause a rotation always in the same direction of the follower or cross bar 52 in proportion to the movement of the parts with which 30 the apparatus is associated, and to which it supplies a fluid, such as a lubricant, and that when a predetermined amount of movement of the member 52 has taken place, it will drop off the abrupt shoulders 51 on the cam members 59, 35 causing the spring, which has been compressed as the member 52 has ridden up the inclined faces of the cam members 59, to project the plunger 44 by snap action into the passage 37, compressing the lubricant therein and forcing 40 it to unseat the ball valve 35 and passing it at high pressure into the valve chamber 33 and thus into the oil passage 28 leading to the bearing that the device is to lubricate. It is, of course, understood that the hollow nipple 42 has a passage 45 that connects with the passage 69 leading into the chamber 70 formed between the base member 22 and the housing 21, which acts as a lubricant reservoir or chamber and with which the passage 49 connects to supply lubricant to 50 the cylinder or bore 37 in which the plunger operates.

Referring now to Figs. 12, 13, 14 and 15, the base member 22' is made in a very similar manner to the base member 22, and the externally screw threaded portion 32 is provided with a valve mechanism, which is substantially the same as previously described and bears the same reference numerals, the valve chamber and the bore or cylinder portion 37 leading into the same being 60 made in substantially the same manner and being related to each other in the same manner as previously described in connection with Figs. 3 and 4. The passage 39 leads to the bore 37 from the passage 48 in the same manner as previously described and the conduit 30 is connected with the base portion 22' in the same manner as has been previously described in connection with Fig. 3.

The plunger rod 44' operates in a guide passage 70 43 in the same manner as previously described and cooperates with the bore 37 in a similar manner to that of the plunger rod 44. The plunger rod 44' extends through an opening in the follower 52', which is channel shaped in cross 75 section, and the plunger rod 44' is provided with

wings 71 thereon that are formed by flattening portions of said plunger rod 44' for the purpose of holding the plunger rod assembled with the follower 52', and the follower 52' is provided with a transverse wall portion 72 acting as a bearing member against which the compression spring 56 engages, the spring 56 shown in Fig. 12 being similar to the spring 56 shown in Fig. 3 and serving a similar purpose, as will become apparent as the description proceeds. The follower 10 52' is further provided with an extension or wing portion 73 similar to the extension 59 on the follower 52. The follower 52' further cooperates with the cam on the base member 22', said cam being constructed in the same manner as that 15 shown in Fig. 3 and the same numerals are applied thereto.

The housing member 21' embraces the base member 22' in a similar manner to that in which the housing 21 embraces the base member 22, 20 and a gasket member 46 is provided for sealing the joint between the housing and base members in the same manner as shown in Fig. 3. The driving means for the follower 52' mounted in the housing portion 21' is, however, quite different from that shown in Fig. 3 for driving the follower 52 always in one direction. Said driving mechanism comprises a double ball clutch mechanism, one ball clutch device being used for driving the follower 52' in a clockwise direction 30 relative to the cam portions provided on the base 22', and the other ball clutch member being provided to hold said follower from reverse movement relative to the base member 22'.

The double ball-clutch mechanism comprises the inner disk members 74 and 75, between which are mounted a ball retaining thin sheet metal disk 76, there being also a sheet metal ball retaining disk 77 provided between the head 78 on the tubular rivet-like member 79 and the member 74, and there being a sheet metal disk-like member 80 provided between the head or flange 81 formed by upsetting the tubular end of the rivet 79 and the disk member 76, said disk member 80 having an ear or extension 82 45 thereon, which acts as a finger engaging with the finger or extension 73 on the follower 52'. The members 77, 74, 76, 75 and 80 are thus all secured together to rotate as a unit with the tubular rivet 79. 50

A ring-like member 83 is mounted in a socket portion provided adjacent the closed end wall 84 of the housing member 21', being mounted in the same so as to rotate with the housing member 21. The ring 83 is angular in cross section, having an 55 annular flange 85 on the same surrounding the circular opening provided in the ring. A plurality of balls 86 is mounted between said flange 85 and cam faces 87 provided on the periphery of the disk 74, there being outward extensions 60 or lugs 88 on the disk 74 between the cam portions to serve as abutments for the compression springs 89, which tend to force the ball members toward the narrow portions of the passages formed between the cam members 87 and the 65 flange 85, said extensions 88 being spaced slightly from the flange 85 so as to permit free rotation of the member 74 relative to the ring 83 when this is desired.

It will be seen that when the ring 83 is rotated in a clockwise direction relative to the base member 22' as viewed in Fig. 13, the tendency will be for this rotation of the ring 83 along with the housing member 21' to crowd the balls 86 into the narrow portions of the passages between 75

the cams 87 and the flange 85, thus wedging the balls into such position as to cause the disk 74 to be rotated in a clockwise direction with the ring 83, and thus carry the finger 82 along therewith, and also the follower 52' through the finger or extension 73, which is in engagement with the finger 82. Any reverse rotation of the member 21' relative to the member 22 would tend to cause the balls 86 to move to the wider portions 10 of the passages between the cam faces 87 and the flange 85, thus releasing the grip of the balls on the member 14 and causing the member 74 to remain stationary with the member 22' instead of moving with the member 21'.

15 To assure such release of the member 74 and prevent any reverse rotation of the follower 52', a second ball clutch mechanism is provided, which comprises the disk-like member 75 having the cam faces 90 thereon, which are inclined in the same direction as the cam faces 87 and having the ears or projections 91 interposed between the cam faces to serve as abutments for the springs 92, which tend to crowd the balls 93 toward the narrower portions of the passages provided between the cam faces 90 and the inner face of the cylindrical ring-like member 94, which is mounted between the cylindrical extension 95 on the base member 22' and the member 75, and is fixed on the extension. Any tendency of the housing member 21' in its counter-clockwise rotation to carry the member 74 and thus the member 75 along with it in a counter-clockwise direction will cause the balls 93 to wedge 35 in the narrower portions of the passages between the cam faces 90 and the ring 94 thus holding the member 75, and thus the follower 52', from counter-clockwise rotation relative to the base portion 22'.

40 The housing portion 21' is provided with an externally threaded nipple 96 projecting therefrom for connection of a conduit therewith, there being a passage 97 provided leading from this nipple into the interior of the housing and the cylindrical wall portion 95 having openings 98 therein leading into the chamber 99 provided within the same, which communicates with the passage 40. The type of device shown in Figs. 12, 13, 14 and 15 is preferably used where a very 45 small amount of movement of the parts with which the fluid feeding device is associated occurs under normal conditions and such a feeding device having the housing portion 21' and the base portion 22' is shown in Fig. 1 as associated with the shackle bolt 100, which has a lubricant passage 101 therein leading to the bearing portion 102 provided on the end of the spring 103, the conduit portion 30 leading to the base portion 22' and a conduit portion 104 leading 50 from the housing portion 21' and being secured to the spring 103 by any suitable clamping means 105 so as to be fixed relative to the spring. The housing 21' is thus fixed relative to the spring, whereas the base portion 22' is fixed relative to 55 the shaft or shackle bolt 100. It will be obvious that the clutch mechanism described will rotate the member 52' always in the same direction in unison with movements of the housing member 21' relative to the base member 22' in a clockwise direction only, and that the movement of 60 said follower or cross bar 52' along the cam will be in proportion to the oscillating movement of the spring relative to the shackle bolt or any other two parts with which the fluid feeding device is associated. It will also be apparent that

the follower in cooperation with the cam and the spring will produce feeding strokes by snap action of the plunger rod 44' in a manner such as that previously described in connection with Figs. 3 to 11, inclusive.

5 In Figs. 16 and 20 a further modification of the invention is shown, which provides a simplified structure, as compared with that shown in Figs. 12 to 15 inclusive, one of the ball-clutch members being omitted. The base portion 22'' is 10 made substantially in the same manner as previously described in connection with Figs 12 to 15, the same reference numerals being applied to corresponding parts in Figs. 12, 13, 14, 15, 16 and 20. Instead of providing the inturned flange 38 15 for holding the spring 34 in position in Fig. 16, a cross pin 106 is shown in the valve chamber 33.

The cam member 50 is made in substantially the same manner as previously described, having the abrupt shoulder 51 thereon, and the housing 20 or cap portion of the device is made in the form of a sheet metal cap member 107, which has an outwardly offset portion 108 along the peripheral edge thereof, which embraces the gasket member 46 and clamps the gasket member in fixed position on the sheet metal cap member 107, said sheet metal cap member having a curved end wall 109 and having a nipple 110 formed thereon in which a tubular member 111 is fixed in liquid-tight relation in any desired manner. Mounted in the cap member so as to be fixed in position therein is a ring-like member 112, which cooperates with the cam member 74 made in the same manner as previously described, the member 112 taking the place of the ring 83 and 30 the balls 86 being mounted between the ring member 112 and the cam faces provided on the cam member 74, said cam member being made substantially as shown in Fig. 13.

40 The hollow tubular rivet 79' holds a cup-like member 113 in fixed position on the member 74 to rotate therewith, said member 113 serving as a ball retaining disk, the balls being confined between this member 113 and the end wall 109. A spring 56' is mounted between the end wall of 45 the cup-like member 113 and a cross bar 114 is provided on the plunger rod 44'', which is adapted to enter the passage 37 to feed fluid into the valve chamber 33 in the manner previously described. The cross bar 114 is made in the same 50 manner as the cross bar 52 except that it has no projection thereon and is mounted on the plunger 44'' in the same manner, and engages with the cam faces 50 in the same manner as the cross bar or follower 52', or the cross bar or follower 52, and the spring 56' causes snap action 55 feeding movements of the plunger 44'' in the same manner as does the spring 56 in Figs. 3 and 12.

60 It will be obvious that clockwise rotation of the cap member or housing 107 relative to the base member 22'', will cause the cam member 74 to be rotated to carry the cup-like member 113 therewith. Said cup-like member is provided with a pair of substantially diametrically opposed 65 slots 115, into which the ends of the cross bar 114 extend so that the cross bar will rotate in unison with the member 113. The cup-like member is provided with a peripheral flange 116, which engages with the shoulder 117 formed on 70 the base member 22'', the parts being so proportioned that the cup-like member 113 will have frictional engagement with the cylindrical wall portion 118 on the base member 22'' and with the shoulder 117 through the flange 116 when 75

the parts are in assembled relation, and accordingly when the casing or housing member 107 rotates in a counter-clockwise direction relative to the base member 22'', this frictional drag of the cup-like member 113 on the base member 22'' will cause the member 113 and the cross bar 114 to remain stationary with the member 22'' upon such counter-clockwise rotation of the housing member 107 and the balls 86 will travel to the wider part of the passages provided for the same between the member 74 and the member 112, thus permitting the housing and the ring-like member 112 to rotate freely on the member 74, without any reverse movement of the cross bar 114. Thus the movements of the cross bar 114 will be in proportion to the movements of the housing member relative to the base member in one direction and the feeding strokes of the plunger 44'' will be controlled thereby in a similar manner to that previously described in connection with the other forms of the invention.

Referring now to Figs. 17, 18 and 19, the form of the invention shown therein comprises a casing or housing 120 of a cup-like form having an integral end wall portion 121 and having a disk-like closure member 122 secured to the casing 120 by clamping the edges thereof along the circumferential edge of the member 122, to clamp said edge in the groove 123 formed by means of the outwardly directed annular offset 124 and the inturned flange 125 provided on the casing member 120. A base member 126 is provided with an externally screw threaded portion 127 thereon for connection with any suitable device that is to be lubricated, said base member cooperating with the casing 120. Mounted within the base member 126 is a tubular member 128 upon which the sleeve 129 is mounted in fixed position. The disk-like member 122 is somewhat dished in form and is provided with an inturned annular flange portion 130, rotatably mounted on the sleeve 129. The tubular member 128 is provided with a lateral annular enlargement 131 adjacent one end of the bearing sleeve 129 and with a tubular end portion 132 extending endwise therefrom. The enlargement 131 is provided with a lateral opening 133 therein.

A ring-like driving clutch disk 134 is mounted in fixed position on the casing 120, being clamped in the groove 123 along with the disk 122. The driving clutch disk 134 is shown more in detail in Fig. 18 and is provided with curved cam faces 135 formed in the inner edge thereof, said cam faces 135 being curved on a gradually decreasing radius of curvature from a point nearest the inner edge of the disk 134 to a point the farthest from said inner edge at the shoulders 136. A cam member 137 is provided which is made up of the cylindrical wall portion 138 having a cam surface provided on the edge portion thereof and a flange 139 extending inwardly from said cylindrical portion 138. Ball members 140 are mounted between the cylindrical wall portion 138 and the cam faces 135 of the clutch disk 134 and coil springs 141 are mounted between the ball members 140 and the end walls 136 provided in the recesses formed in the inner periphery of the disk 134 to provide the cam faces 135.

Referring to Fig. 18 it will be seen that inasmuch as the surface 135 of each cam portion approaches the member 138 in a counter-clockwise direction, rotation of the disk 134 in a clockwise direction will wedge the balls 140 between the cylindrical wall portion 138 of the clutch member 137 and the cam faces 135 of the disk 134, the

balls being held in position ready for engagement with the members 138 by the springs 141. As a result, a clockwise movement of the disk-like member 134 will immediately cause the cam member to be carried along with the member 134 in a clockwise direction. 5

The flange 139 of the clutch member 137 is provided with recesses in the inner periphery thereof forming the cam faces 143 extending between the shoulders 142 and 144. The cam faces 143 are inclined in an opposite direction to the cam faces 135 on the disk 134. Balls 145 are mounted between the bearing member 129 and the cam faces 143 on the flange 139, being held in engagement with the cam faces 143 and the cylindrical outer surface of the bearing member 129 by means of coil springs 146 mounted between the shoulders 144 and balls 145. As the cam surfaces 143 approach the bearing member 129 in a clockwise direction, any tendency of the cam member 137 to rotate in a counter-clockwise direction with the disk 144 will cause the balls 145 to wedge between the cylindrical outer wall portion of the bearing member 129 and the cam faces 143 to hold said cam members 137 from such counter-clockwise rotation.

It will accordingly be seen that a rotation relative to the base member 126 of the casing 120 in a clockwise direction will move the cam member 137 in the same direction through the same arc 30 as the member 120 relative to the member 126, but the rotation of the casing 120 in a counter-clockwise direction relative to the base member 126 will not cause the cam member 137 to move at all, whereby the cam member 137 will move in a 35 constant direction in exact proportion to the movement of the casing 120 relative to the base member 126, whether the relative movement is constant or intermittent in a predetermined direction or an oscillation. The ball and disk 40 clutch members provided by the disk 134 and the flange 139 are responsive to even the slightest movement of the parts to cause the cam to move with the driving disk 134 in one direction and will be held from any movement whatsoever with the driving disk 134 relative to the bearing member 129 in the opposite direction.

The end of the bearing member 129 adjacent the lateral enlargement 131 in the tubular member 138 is bevelled as shown in 147 to permit the 50 end portion of the member 129 to engage snugly with the bottom wall 148 of the enlargement 131, said wall portion 148 thus serving to hold the ball members 145 in position and locking the member 129 in fixed position between the member 126 and 55 the wall 148. The washer 149, angular in cross-section, is provided upon the cylindrical portion 138 of the cam 137 to hold the balls 140 in position. The tubular member 128 is provided with transversely aligning openings 150 therein that 60 align with the passage 151 in the base member 126, said passage 151 extending through the externally threaded tubular extension 152 on the base member 126.

The upper edge portion of the cylindrical cam 65 portion 138 of the cam member 131 is formed so as to provide the inclined cam faces 153 that correspond to the cam faces 50 in the form shown in Figs. 3 to 11, inclusive, except that the same are oppositely inclined, the same extending upwardly from a low point 154 to an abrupt shoulder at the high point 156 thereof. Thus the cam surface comprises two gradually inclined faces 153 that lie diametrically opposite each 70 75

other and two abrupt shoulders forming duplicate cam members.

The tubular end portion 132 of the tubular member 128 is provided with a pair of oppositely arranged slots 157 through which the bar 158 extends. The bar 158 is of sheet metal and the opposite ends thereof are cut away to form shoulders at 159 with which the coil spring 160 of relatively large size engages at one end thereof. The other end of the spring 160 engages with the end wall 121 of the casing 120. A laterally extending externally threaded nipple 161 is provided on the casing 120 with which the pipe section 162 is connected by means of a union 163 of any standard construction. The bar 158 is provided with substantially straight projecting foot portions 164 engaging with the cam faces provided on the upper edge of the cylindrical portion 132 of the cam 137, being held in engagement therewith by means of the coil spring 160, said cross bar thus serving as a follower bar or follower member engaging said cam.

Mounted within the tubular member 128 is a valve and pump body portion 165 having a head 166 on the outer end thereof and being provided with a bore 167 therein, slidably receiving the plunger rod 168, said plunger rod having a head 169 thereon and having curved surfaces 170 thereon engaging with the curved surface of the opening 171 in the follower bar 158, the wall of the opening 171 being curved to correspond with the curvature of the opposite ends of the head 169 to provide a universally tiltable connection between the plunger and follower.

As the head 169 is mounted within the opening 171 in the bar 158 any movement of the bar 158 in the direction of the axis of the plunger 168 will be transmitted to said plunger. Thus, as the follower bar 158 is moved gradually toward the end wall 121 as the foot portions 164 thereof move upwardly along the inclined cam faces 153 during the rotation of the cam 137, the plunger 168 is moved endwise toward the end wall 121 an amount in proportion thereto. This movement will continue until the highest points on the cam faces 153 are reached, whereupon the member 158 will drop off the shoulders of the cam with a snap action due to the pressure of the spring 160 and the plunger 168 will be moved in a feeding direction by snap action. The number of said movements of the plunger will accordingly be directly proportional to the movement of the member 120 relative to the member 126, as previously described in connection with the other forms of the invention, and the amount of fluid fed through the bore 167 due to the movement of the plunger 168 will be in proportion to the movement of the member 120 relative to the member 126.

The fluid is free to pass in either direction from the pipe 162 to the tubular projection 152, through the casing 120, and the tubular member 128 due to the provision of the openings 133 and 150 in the tubular member 128, the one end portion 172 of the member 165 being reduced to provide an opening through the tubular member 128 around said member 165 to said openings 150. The reduced portion 172 of the member 165 is also provided with a transverse opening 174 aligning with the openings 150 and with a longitudinal bore 175 aligning with the bore 167, the opening 174 supplying fluid to the bore 175. The plunger rod 168 is projected into the bore 175 in which it has a sliding fit when the follower member 158 drops off the shoulders of

the cam to feed the fluid into the enlarged passage 176 in the member 165.

The passage 176 has a valve seat in the end wall 177 against which the ball-valve member 178 seats, said ball valve member being held in engagement with said seat by means of the coil spring 179 held under compression between the ball 178 and the inwardly directed flange 180 on the member 165. The head 166 has a conical surface 181 thereon and the base member 126 is bevelled at 182, the tubular member 128 being swaged outwardly therebetween to firmly hold the members 126, 128 and 165 in assembled relation.

The rotation of the member 120 relative to the base 126 is accomplished due to relative movement of the pipe section 162, and the pipe section connected with the tubular member 152, the pipe section 162 and the member 126 being carried by two relatively movable parts with which the fluid feeding device is associated.

What is claimed is:—

1. In a device of the character described, fluid feeding means comprising a pair of relatively rotatable members, a feeding member movable in opposite directions, and means for moving the same in both directions, said means for moving said feeding member comprising resilient means for moving the same in a feeding direction, a movable controlling member moving said feeding member in the opposite direction and controlling the feeding movements of said feeding member due to the action of said resilient means, and means for moving said controlling member upon slight relative movement of said relatively rotatable members in one direction comprising a driving connection between said controlling member and one of said relatively rotatable members comprising a one-way clutch interposed between the rotatable member and the controlling member to move said controlling member upon rotation of said relatively rotatable member in a predetermined direction, and a one-way clutch interposed between the other of said relatively rotatable members and said controlling member operating to hold said members against relative rotation in a reverse direction only. 35

2. In a device of the character described, fluid feeding means comprising a pair of relatively rotatable members cooperating to provide a fluid tight chamber, a feeding member movable in opposite directions, and means for moving the same in both directions, said means for moving said feeding member comprising resilient means for

moving the same in a feeding direction, a movable controlling member moving said feeding member in the opposite direction and controlling the feeding movements of said feeding member due to the action of said resilient means and means for moving said controlling member upon slight relative movement of said relatively rotatable members in one direction comprising, a one-way clutch device interposed between said controlling member and one of said relatively rotat- 50

able members providing means for moving the same in unison in one direction and a one-way clutch device interposed between said controlling member and the other of said relatively rotatable members providing means for moving said con- 55

trolling member and said last mentioned rotatable member in unison in the opposite direction, whereby said controlling member will be driven by said clutch device in one direction only relative to one of said relatively rotatable members. 60

3. In a device of the character described, fluid feeding means comprising a pair of relatively rotatable members, a feeding member movable in opposite directions, and means for moving the same in both directions, said means for moving said feeding member comprising resilient means for

moving the same in a feeding direction, a movable controlling member moving said feeding member in the opposite direction and controlling the feeding movements of said feeding member due to the action of said resilient means and means for moving said controlling member upon slight relative movement of said relatively rotatable members in one direction comprising, a one-way clutch device interposed between said controlling member and one of said relatively rotat- 65

able members providing means for moving the same in unison in one direction and a one-way clutch device interposed between said controlling member and the other of said relatively rotatable members providing means for moving said con- 70

trolling member and said last mentioned rotatable member in unison in the opposite direction, whereby said controlling member will be driven by said clutch device in one direction only relative to one of said relatively rotatable members. 75

3. In a device of the character described, a pair of relatively movable housing and base members cooperating to provide a fluid chamber, a reciprocable plunger and means to produce each feeding stroke of said plunger in proportion to a predetermined amount of relative movement of said housing and base members in a predetermined direction, comprising means tending to move said plunger in a feeding direction, a movable controlling member directly connected with said plunger and releasing the same after said controlling member has moved through a predetermined distance to permit said means to produce a feeding stroke of said plunger, and means for positively driving said controlling member by the relative movements of said housing and base members in said direction, comprising a one-way clutch mechanism for moving said controlling member in one direction and a one-way clutch mechanism for holding said controlling member against reverse movement upon relative movement of said housing and base members in a reverse direction.
4. In a device of the character described, relatively movable housing and base members cooperating to provide a fluid chamber, a reciprocable plunger and means to produce a feeding stroke of said plunger comprising resilient means for moving said plunger, and controlling means for said plunger comprising a pair of relatively movable controlling elements cooperating to hold said plunger from movement under the action of said resilient means until a predetermined relative movement of said controlling elements has taken place and thereupon releasing said plunger for movement through a feeding stroke, and means for moving one of said controlling elements in unison with one of said first mentioned members in one direction only, comprising a one-way driving clutch and a one-way holding clutch.
5. In a device of the character described, relatively movable housing and base members cooperating to provide a fluid chamber, a reciprocable plunger and means to produce a feeding stroke of said plunger comprising resilient means for moving said plunger, and controlling means for said plunger comprising a pair of relatively movable controlling elements cooperating to hold said plunger from movement under the action of said resilient means until a predetermined movement of said controlling elements has taken place, and thereupon releasing said plunger for movement through a feeding stroke, and means for moving one of said controlling elements in unison with one of said first mentioned members in one direction only, comprising a one-way ball driving clutch and a one-way ball holding clutch.
6. In a device of the character described, relatively movable housing and base members, a reciprocable plunger and means to produce a feeding stroke of said plunger comprising resilient means for moving said plunger, and controlling means for said plunger comprising a pair of relatively movable controlling elements cooperating to hold said plunger from movement under the action of said resilient means until a predetermined movement of said controlling elements has taken place and thereupon releasing said plunger for movement through a feeding stroke, and means for moving one of said controlling elements in unison with one of said first mentioned members in one direction only, comprising a one-way expansible driving clutch and a one-way expansible holding clutch.
7. In a device of the character described, relatively movable housing and base members, a reciprocable plunger and means to produce a feeding stroke of said plunger comprising resilient means for moving said plunger, and controlling means for said plunger comprising a pair of relatively movable controlling elements cooperating to hold said plunger from movement under the action of said resilient means until a predetermined movement of said controlling elements has taken place and thereupon releasing said plunger for movement through a feeding stroke, and means for moving one of said controlling elements in unison with one of said first mentioned members in one direction only, comprising a one-way expansible driving clutch and a one-way expansible resilient holding clutch.
8. The combination with a pair of relatively movable parts having engaging surfaces, of means for lubricating said surfaces comprising a pair of relatively movable members cooperating to provide a fluid tight chamber, the said relatively movable members being connected with the respective movable parts to move therewith, a reciprocable feeding member in said chamber and means for producing a feeding stroke of said feeding member after a predetermined amount of relative movement of said pair of parts comprising a movable controlling element for said feeding member, and a one-way clutch for driving said controlling element by means of one of said relatively movable members when the same moves in one direction, and a one-way clutch for holding said controlling element against movement with said movable member upon movement of the same in the opposite direction.
9. The combination with a pair of relatively movable parts having engaging surfaces, of means for lubricating said surfaces comprising a pair of relatively movable members cooperating to provide a fluid tight chamber, the said relatively movable members being mechanically connected with the respective movable parts to move positively therewith, a reciprocable feeding member in said chamber and means for controlling the feeding strokes of said feeding member comprising a controlling element rotatable relative to one of said relatively rotatable members, a cooperating controlling element fixed relative to said last mentioned movable member, means providing a mechanical driving connection between the other relatively movable member of said pair and said rotatable controlling element to rotate the same together in only one direction, and a one-way clutch for holding said rotatable controlling element against movement relative to its cooperating controlling element in a reverse direction.
10. In a device of the character described, a body portion having a bore therein, a reciprocable feeding member mounted in said body portion, a housing movably mounted on said body portion, means for controlling the feeding movements of said feeding member, comprising a cam element and an element engaging said cam element, one of said elements being mounted in fixed position on said body portion, a one-way clutch mechanism for moving the other of said elements with said housing in one direction and a one-way clutch mechanism for holding said last mentioned element from movement with said housing in the opposite direction.
11. In a device of the character described, a body portion having a bore therein, a feeding member mounted for reciprocation in said bore,

a housing rotatably mounted on said body portion, controlling means for said feeding member comprising a cam fixed on said body portion, a cross member engaging said cam and connected with said housing through mechanism comprising a one-way ball driving clutch for moving said cross member with said housing in one direction and means for fixing the same relative to said body portion during movement of said housing in the opposite direction relative to said body portion.

12. In a device of the character described, fluid feeding means comprising reciprocable means and means for reciprocating the same comprising a pair of relatively movable members forming a fluid tight chamber containing said fluid feeding means, and actuating means for said reciprocable means comprising a clutch member connected with one of said relatively movable members, a cam member actuated by movements of said clutch member in one direction upon slight relative movement of said relatively movable members in one direction, and means for holding said cam member against reverse movement.

13. A device of the character described comprising a pair of housing and base members cooperating to provide a fluid chamber and having means for attachment to a pair of relatively movable parts to move therewith, and fluid feeding means actuated by said members through a one-way driving mechanism, said one-way driving mechanism comprising controlling mechanism, an expansible resilient member for driving said controlling mechanism in one direction, and means for holding said controlling mechanism from movement in the opposite direction.

14. In a device of the character described, fluid feeding means comprising reciprocable means and means for reciprocating the same, comprising a pair of relatively movable members cooperating to provide a fluid chamber containing said fluid feeding means, and actuating means for said reciprocable means comprising an expanding clutch mechanism connected with one of said relatively movable members and operating to

move said reciprocable means upon relative movement of said members in one direction.

15. In a device of the character described, fluid feeding means comprising reciprocable means and means for reciprocating the same, comprising a pair of relatively movable housing and base members cooperating to provide a fluid chamber, and actuating means for said reciprocable means comprising an expanding clutch mechanism connected with one of said relatively movable members and operating to move said reciprocable means upon relative movement of said members in one direction, and comprising expanding resilient means for holding said controlling mechanism from reverse movement.

16. In a device of the character described, comprising a pair of members forming a fluid chamber and having means for attachment to a pair of relatively movable parts to move therewith and fluid feeding means in said chamber actuated by slight relative movement of said members in one direction through a one-way driving mechanism, said one-way driving mechanism comprising controlling mechanism, an expansible resilient member for driving said controlling mechanism in one direction, and means for holding said controlling mechanism from movement in the opposite direction.

17. In a device of the character described, a body portion having a bore therein, a reciprocable feeding member mounted in said body portion, a housing movably mounted on said body portion, means for controlling the feeding movements of said feeding member, comprising a cam element and an element engaging said cam element, one of said elements being mounted in fixed position on said body portion, expansible resilient means for moving the other of said elements with said housing in one direction, and expansible resilient means for holding said last mentioned element from movement with said housing in the opposite direction.
